3 Claims 10

ABSTRACT OF THE DISCLOSURE

Compounds of the class of substituted p-aminoalkylphenylsulfonyl-2-imino-imidazolidines and the pharmaceutically acceptable acid addition salts thereof have hypoglycemic activity; these compounds are active ingredients of pharmaceutical compositions and are useful for the treatment of diabetes mellitus; a typical embodiment is 1 - [p - [2 - (ethoxycarbonylamino)-ethyl]-phenylsulfonyl]-2-imino-3-cyclohexyl-imidazolidine.

The present invention relates to derivatives of p-aminoalkylphenylsulfonyl-2-imino-imidazolidines, to pharmaceutical compositions containing these compounds and to their use.

More particularly, the present invention relates to compounds of formula

wherein

R₁ is alkyl having from one to six carbon atoms, cycloalkyl or cycloalkenyl having from five to eight carbon atoms, or allyl;

R₂ is hydrogen, methyl or ethyl;

R₃ is alkyl having from one to six carbon atoms, cycloalkyl having at most eight carbon atoms, allyl, phenyl or phenylalkyl having at most nine carbon atoms;

m is the integer 2 or 3;

and the pharmaceutically acceptable acid addition salts thereof.

These compounds have been found to have a hypoglycemic effect in warm-blooded animals upon oral or parenteral administration. This activity, in combination with a favourable therapeutic index, characterizes the compounds of the present invention as being suitable for the treatment of diabetes mellitus.

The therapeutic action can be demonstrated in standard tests on experimental animals.

In the compounds of Formula I, R₁, as alkyl, can be e.g. the methyl, ethyl, propyl, isopropyl, butyl, sec.butyl, tert.butyl, isobutyl, pentyl, isopentyl, 2,2-dimethylpropyl, 1-methylbutyl, 1-ethylpropyl, 1,2-dimethylpropyl, n-hexyl, methylpentyl, dimethylbutyl or ethylbutyl group. As cycloalkyl, R₁ can be the cyclopentyl group which can be optionally substituted by alkyl groups having one to three carbon atoms, the cyclohexyl group which can be substituted by ethyl or methyl, and the cycloheptyl group optionally substituted by methyl, as well as the cyclooctyl group. As cycloalkenyl, R₁ can be the 2-cyclopenten-1-yl, the 2-cyclohexen-1-yl, the 3-cyclohexen-1-yl, the 2-methyl-2-cyclohexen-1-yl, the 3-cyclohepten-1-yl group, or a cyclooctenyl group.

The substituent R₃ comprises the same alkyl and cyclo-

2

alkyl groups which were mentioned for R₁; as the phenylalkyl group, R₃ can be the benzyl group, the phenylethyl group or the α -methylphenylethyl group.

Using the process according to the invention, compounds of Formula I are produced by reacting a compound of formula

wherein

R₁, R₂ and m have the meaning given under Formula I, with a compound of formula

wherein

R₃ has the meaning given under Formula I, and X represents a halogen atom or an acyloxy group derived from a monoester of carbonic acid,

and optionally converting the reaction products obtained into the salt of an inorganic or organic acid.

As compounds of Formula III, chloro- and bromoformates are particularly suitable in which R₃ has the meaning given under Formula I. Suitable acyloxy compounds of Formula III are pyrocarbonic acid esters of

wherein R₃ has the meaning given under Formula I. These substances can, for example, be obtained by reacting chloroformates with alkali-metal salts of monoesters of carbonic acid. Mixed pyrocarbonic acid esters may, however, also be used. In this case one of the R₃ radicals represents a methyl or an ethyl group. W Thoma, H. Rinke [Liebigs Ann. Chem. 624, 30 (1959)].

The reaction is performed for example at temperatures between -20° and $+20^{\circ}$ C. in an inert organic solvent. Suitable examples are: hydrocarbons such as benzene, toluene or xylene, ethers such as diethylether, dioxane or tetrahydrofuran, chlorinated hydrocarbons such as methylene chloride, and lower ketones such as acetone or methyl ethyl ketone.

A chloroformate of Formula III is reacted according to the invention preferably in the presence of an acid-binding agent. For this purpose inorganic bases or salts such as, for example, an alkali hydroxide, acetate, hydrogen carbonate, carbonate or phosphate such as sodium hydroxide, acetate, hydrogen carbonate and phosphate, or the corresponding potassium compounds may be used. In addition, calcium oxide, carbonate, and phosphate, and magnesium carbonate may also be used. Instead of inorganic bases or salts, organic bases such as, for example, pyridine, trimethyl- or triethylamine, diisopropylamine, or collidine are suitable. When these are used in excess they can also be used as solvent.

Instead of amines of the general Formula II, in the reaction according to the invention with a chloroformate, N-alkali metal derivatives of these compounds, e.g. sodium, potassium or lithium derivatives may also be employed.

The starting materials of the general Formula II are new compounds and can be produced, e.g. by reacting a reactive derivative of a sulphonic acid of formula

wherein

R represents a simple alkyl or aryl radical, for example a methyl or a phenyl group, and
m has the meaning given in Formula I,
with 2-amino-2-imidazoline derivatives of formula

wherein

R₁ and R₂ have the meaning given under Formula I, and then hydrolytically cleaving off the acyl protective grouping (R—CO—). The N-acyl compounds derived from those of Formula II which are obtained as intermediates have likewise previously not been described in the literature.

Suitable reactive derivatives of a sulphonic acid of Formula V are halides, especially chlorides and anhydrides of formula

wherein m has the meaning given under Formula I.

The anhydrides of Formula IVa can be obtained in a simple manner by the reaction of corresponding substituted sulphonic acid halides with salts of corresponding substituted sulphonic acids.

Using a further process, starting materials of the Formula II are obtained by reacting substituted p-(aminomethyl)-benzenesulphonamides (produced analogously to the method of E. Miller, J. Amer. Chem. Soc. 62, 2101 (1940)) of formula

wherein m has the meaning given under Formula I, with substituted N-(2-bromoalkyl)-cyanoamides in an alkaline medium.

The starting materials of Formula III are prepared by the commonly known methods for chloroformates.

The new substances of Formula I, or the pharmaceutically acceptable acid addition salts thereof, can be administered orally or parenterally. For salt formation, it is possible to use physiologically suitable inorganic or organic acids such as, e.g. hydrochloric acid, hydrobromic acid, sulfuric acid, phosphoric acid, methanesulfonic acid, acetic acid, lactic acid, succinic acid, tartaric acid and maleic acid, but also hypoglycemic sulfonyl ureas such as, e.g. p-toluenesulfonylbutyl urea, p-chlorobenzenesulfonyl-propyl urea and p-[2-(2-methoxy - 5 - chlorobenzamido)-ethyl]-phenylsulfonyl-cyclohexyl urea.

For their intended use, the compounds of the invention are administered in amounts depending on the species, the age, weight and the particular condition of the individual being treated, and the mode of administration. In general, the daily dosage varies between about 0.1 and 100 mg./kg. of body weight for warm-blooded animals. Suitable dosage units, such as dragées and tablets, contain preferably 10-200 mg. of an active substance according to the invention, whereby the content of active substance is 20-80% by weight. The tablets and dragées are produced by combining the active substance, e.g. with solid pulverulent carriers such as lactose, saccharose, sorbitol or mannitol; starches such as potato starch, maize starch or amylopectin, also laminaria powder or citrus pulp powder; cellulose derivatives or gelatine, optionally with the addition of lubricants such as magnesium or calcium stearate or polyethylene glycols of suitable molecular weights. Tablets and dragée cores are coated, e.g. with

concentrated sugar solutions which may also contain, e.g. gum arabic, talcum and/or titanium dioxide, or with a lacquer dissolved in readily volatile organic solvents or mixtures of solvents. Dyestuffs can be added to these coatings, e.g. for identification of the various dosages of active substance.

Other suitable dosage units for oral administration are hard gelatine capsules, as well as soft closed capsules made from gelatine and a softener, such as glycerin. The hard capsules contain the active substance preferably as a granulate, e.g. in admixture with fillers such as maize starch, and/or lubricants such as talcum or magnesium stearate, and optionally stabilizers such as sodium metabisulphite (Na₂S₂O₅) or ascorbic acid. In soft capsules, the active substance is preferably dissolved or suspended in suitable liquids such as liquid polyethylene glycols, whereby likewise stabilizers can be added.

The following prescriptions serve to further illustrate the production of tablets and dragées:

(a) An amount of 1000 g. of 1-[p-(2-butoxycarbonylaminomethyl)-phenylsulphonyl]-2-imino - 3 - ethyl-imidazoline is mixed with 500 g. of lactose and 270 g. of potato starch; the mixture is then moistened with an aqueous solution of 8.0 g. of gelatine, and granulated through a sieve. After drying of the granulate, 60.0 g. of potato starch, 60.0 g. of talcum, 10.0 g. of magnesium stearate and 20.0 g. of colloidal silicon dioxide are mixed in; the mixture is then pressed to form 10,000 tablets each weighing 200 mg. and each containing 100 mg. of active substance. Optionally, the tablets may be provided with grooves for a more precise adjustment of the dosage amount.

(b) A granulate is produced from 1000 g. of 1-[p-(2-butoxycarbonylaminomethyl)-phenylsulphonyl]-2-imino-3-cyclohexyl-imidazolidine, 345.0 g. of lactose, and the aqueous solution of 6.0 g. of gelatine; the granulate is then mixed, after being dried, with 10.0 g. of colloidal silicon dioxide, 40.0 g. of talcum, 40.0 g. of potato starch and 5.0 g. of magnesium stearate; and the mixture is pressed into 10,000 dragée cores. These are subsequently coated with a concentrated syrup made from 533.0 g. of crystalline saccharose, 20.0 g. of shallac, 75.0 g. of gum arabic, 250 g. of talcum, 20 g. of colloidal silicon dioxide and 1.5 g. of dystuff; and then dried. The obtained dragées each weigh 240 mg. and each contain 100 mg. of active substance.

The following examples further illustrate the production of the new compounds of the general Formula I and of intermediate products not described hitherto; the examples in no way constitute, however, the only embodiments thereof. The temperatures are given in degrees centigrade.

EXAMPLE 1

From a solution of 37.0 g. of 1-[p-(2-aminoethyl)-phenylsulphonyl]-2-imino-3-ethyl-imidazolidine dihydrochloride, M.P. 242-244°, in 50 ml. of water, the base is set free by the addition of 120 ml. of 2 N sodium hydroxide solution and extracted three times with 100 ml. each of methylene chloride. The extract which has been dried with sodium sulphate, is mixed with 11.0 g. of triethylamine and transferred to a dropping funnel which is mounted on a reaction vessel which is fitted with a stirrer and a cooling arrangement. The reaction vessel has a second dropping funnel containing a solution of 13.7 g. of butyl chloroformate in 100 ml. of methylene chloride. The two solutions are then allowed to run into the reaction vessel in such a manner that, per time unit, about equimolar amounts of the reactants flow into it while the temperature is constantly kept between 0 and +10°. After completion of the addition, the reaction solution is stirred for one hour at room temperature, washed with water, dried with sodium sulphate and the methylene chloride is removed by distillation. The residual, crude 1-[p[2 - (butoxycarbonylaminomethyl) - ethyl] - phenylsulphonyl]-2-imino-3-ethyl-imidazolidine dihydrochloride, M.P. 242-244°, is obtained.

nyl]-2-imino-3-ethyl-imidazolidine, after recrystallization from ethyl acetate, melts at 123-124°.

The dihydrochlorides of 1-[p-(2-amino-ethyl)-phenylsulphonyl]-2-imino-imidazolidines of general Formula II with various substituents in the 3-position which are used in this and the following examples as starting materials may, for example, be obtained by reaction of the appropriately substituted 2-amino-imidazolines with p-(2-acylamido-ethyl)-benzene-sulpho-chlorides and subsequent hydrolytic cleavage of the acyl radical with aqueous hydrochloric acid, as is described below for p-[2-aminoethyl]-phenylsulphonyl]-2-imino-3-butylimidazolidine dihydrochloride:

(a) 17.8 g. of 1-butyl-2-imino-imidazolidine hydrochloride are introduced into a solution of 8.5 g. of sodium hydroxide in 85 ml. of water. The clear solution obtained is then treated with a solution of 26.6 g. of p-(2-acetamido-ethyl)-benzene-sulphochloride in 100 ml. of acetone, whereby heat is produced. The mixture is heated for half an hour at 90° and then evaporated in vacuum to dryness. The residual, crude 1-[p-(2-acetamidoethyl)-phenylsulphonyl]-2-imino-3-butylimidazolidine is recrystallized from ethyl acetate and then melts at 130-131°.

p-(2-acetamido-ethyl)-benzene-sulphochloride can be obtained as follows:

16.3 g. of N-phenethyl-acetamido are introduced with stirring into 35.0 g. of chlorosulphonic acid. The mixture obtained is stirred for 2 hours at 60° and then poured onto ice, whereby the crude p-(2-acetamido-ethyl)-benzene-sulphochloride precipitates in crystalline form. It is removed by filtration, dried in vacuum and used directly as crude product.

(b) A solution of 36.7 g. of 1-[p-(2-acetamidoethyl)-phenylsulphonyl]-2-imino-3-butylimidazolidine in 370 ml. of 2 N hydrochloric acid is refluxed for 6 hours and then evaporated in vacuum. The residual oil is taken up in warm ethanol. On cooling, the 1-[p-(2-amino-ethyl)-phenylsulphonyl]-2-imino-3-butylimidazolidine dihydrochloride, M.P. 231-233°, crystallizes.

EXAMPLE 2

Analogously to Example 1 there are obtained: from in each case 39.8 g. of 1-[p-(2-amino-ethyl)-phenylsulphonyl]-2-imino-3-butylimidazolidine dihydrochloride, M.P. 231-233°,

(a) And 10.9 g. of ethyl chloroformate, 1-[p-[2-(ethoxycarbonyl-amino)-ethyl]-phenylsulphonyl]-2-imino-3-butylimidazolidine, M.P. 112-113° (from ethyl acetate).

(b) And 12.1 g. of allyl chloroformate, 1-[p-[2-(allyloxycarbonyl-amino)-ethyl]-phenylsulphonyl]-2-imino-3-butylimidazolidine, M.P. 108-109° (from ethyl acetate),

(c) And 13.7 g. of butyl chloroformate, 1-[p-[2-butoxycarbonyl-amino)-ethyl]-phenylsulphonyl]-2-imino-3-butylimidazolidine, M.P. 114-115° (from ethyl acetate),

(d) And 13.7 g. of isobutyl chloroformate, 1-[p-[2-(isobutoxycarbonyl-amino)-ethyl]-phenylsulphonyl]-2-imino-3-butylimidazolidine, M.P. 137-138°,

(e) And 12.3 g. of isopropyl chloroformate, 1-[p-[2-(isopropoxycarbonyl-amino)-ethyl]-phenylsulphonyl]-2-imino-3-butylimidazolidine, M.P. 115-116°,

(f) And 15.7 g. of phenyl chloroformate, 1-[p-[2-(phenoxy carbonyl-amino)-ethyl]-phenylsulphonyl]-2-imino-3-butylimidazolidine, M.P. 145-146°,

(g) And 17.1 g. of benzyl chloroformate, 1-[p-[2-(benzyloxycarbonyl-amino)-ethyl]-phenylsulphonyl]-2-imino-3-butylimidazolidine, M.P. 106-108°.

EXAMPLE 3

Analogously to Example 1 there are obtained: from in each case 41.0 g. of 1-[p-(2-amino-ethyl)-phenylsulphonyl]-2-imino-3-cyclopentyl-imidazolidine dihydrochloride, M.P. 270° (decomposition),

(a) And 10.9 g. of ethyl chloroformate, 1-[p-[2-(ethoxycarbonyl-amino)-ethyl]-phenylsulphonyl]-2-imino-3-cyclopentyl-imidazolidine, M.P. 111-112°,

(b) And 12.3 g. of isopropyl chloroformate, 1-[p-[2-(isopropoxycarbonyl-amino)-ethyl]-phenylsulphonyl]-2-imino-3-cyclopentyl-imidazolidine, M.P. 167-168°,

(c) And 13.7 g. of butyl chloroformate, 1-[p-[2-(butoxycarbonyl-amino)-ethyl]-phenylsulphonyl]-2-imino-3-cyclopentyl-imidazolidine, M.P. 114-115°,

(d) And 13.7 g. of isobutyl chloroformate, 1-[p-[2-(isobutoxycarbonyl-amino)-ethyl]-phenylsulphonyl]-2-imino-3-cyclopentyl-imidazolidine, M.P. 144-145°,

(e) And 12.1 g. of allyl chloroformate, 1-[p-[2-(allyloxycarbonyl-amino)-ethyl]-phenylsulphonyl]-2-imino-3-cyclopentyl-imidazolidine, M.P. 113-115°.

EXAMPLE 4

Analogously to Example 1 there are obtained: from in each case 42.4 g. of 1-[p-(2-amino-ethyl)-phenylsulphonyl]-2-imino-3-cyclohexyl-imidazolidine dihydrochloride, M.P. 247-250°,

(a) And 10.8 g. of ethyl chloroformate, 1-[p-[2-(ethoxycarbonyl-amino)-ethyl]-phenylsulphonyl]-2-imino-3-cyclohexyl-imidazolidine, M.P. 116-117°,

(b) And 13.7 g. of butyl chloroformate, 1-[p-[2-(butoxycarbonyl-amino)-ethyl]-phenylsulphonyl]-2-imino-3-cyclohexyl-imidazolidine, M.P. 123-124°,

(c) And 15.7 g. of phenyl chloroformate, 1-[p-[2-(phenoxy carbonyl-amino)-ethyl]-phenylsulphonyl]-2-imino-3-cyclohexyl-imidazolidine, M.P. 151-152°.

EXAMPLE 5

Analogously to Example 1 there are obtained from in each case 43.7 g. of 1-[p-(2-amino-ethyl)-phenylsulphonyl]-2-imino-3-(4-methylcyclohexyl)-imidazolidine dihydrochloride, having a decomposition point of 260°,

(a) And 9.5 g. of methyl chloroformate, 1-[p-[2-(methoxycarbonyl-amino)-ethyl]-phenylsulphonyl]-2-imino-3-(4-methylcyclohexyl)-imidazolidine, M.P. 118-120°,

(b) And 10.9 g. of ethyl chloroformate, 1-[p-[2-(ethoxycarbonyl-amino)-ethyl]-phenylsulphonyl]-2-imino-3-(4-methylcyclohexyl)-imidazolidine, M.P. 138-140°.

EXAMPLE 6

Analogously to Example 1 are obtained:

(a) From 42.5 g. of 1-[p-(2-amino-ethyl)-phenylsulphonyl]-2-imino-3-(1,2-dimethyl-butyl)-imidazolidine-dihydrochloride and 10.9 g. of chloroformic acid-ethyl-ester, 1-[p-(2-ethoxycarbonyl-amino)-ethyl]-phenylsulphonyl]-2-imino-3-(1,2-dimethyl-butyl)-imidazolidine, M.P. 75-78°;

(b) From 38.1 g. of 1-[p-(2-amino-ethyl)-phenylsulphonyl]-2-imino-3-allylimidazolidine-dihydrochloride and 10.9 g. of chloroformic acid-ethyl-ester, 1-[p-(2-ethoxycarbonyl-amino)-ethyl]-phenylsulphonyl]-2-imino-3-allylimidazolidine, M.P. 123-125°;

(c) From 42.1 g. of 1-[p-(2-amino-ethyl)-phenylsulphonyl]-2-imino-3-(3-cyclohexen-1-yl)-imidazolidine-dihydrochloride and 16.3 g. of chloroformic acid-cyclohexyl-ester, 1-[p-(2-cyclohexyloxycarbonyl-amino)-ethyl]-phenylsulphonyl]-2-imino-3-(3-cyclohexen-1-yl)-imidazolidine, M.P. 146-148°;

(d) From 43.7 g. of 1-[p-(2-amino-ethyl)-phenylsulphonyl]-2-imino-3-cyclohexyl-4-methylimidazolidine-dihydrochloride and 10.9 g. of chloroformic acid-ethyl-ester, 1-[p-(2-ethoxycarbonyl-amino)-ethyl]-phenylsulphonyl]-2-imino-3-cyclohexyl-4-methylimidazolidine, M.P. 136-138°;

(e) From 43.7 g. of 1-[p-(2-amino-ethyl)-phenylsulphonyl]-2-imino-3-cyclopentyl-4-ethylimidazolidine-dihydrochloride and 10.9 g. of chloroformic acid-ethyl-ester, 1-[p-(2-ethoxycarbonyl-amino)-ethyl]-phenylsulphonyl]-2-imino-3-cyclopentyl-4-ethylimidazolidine, M.P. 75-77°;

(f) From 43.7 g. of 1-[p-(2-amino-propyl)-phenylsulphonyl]-2-imino-3-cyclohexyl-imidazoline-dihydrochloride and 10.9 g. of chloroformic acid-ethyl-ester, 1-[p-(2-ethoxycarbonyl-amino)-ethyl]-phenylsulphonyl]-2-imino-3-cyclohexyl-imidazoline, M.P. 75-77°;

ride and 10.9 g. of chloroformic acid-ethylester, 1-[p-(2-(ethoxycarbonylamino)-propyl) - phenylsulphonyl] - 2-imino-3-cyclohexyl-imidazolidine, M.P. 100-103°;

(g) From 40.9 g. of 1-[p-(2-amino-ethyl)-phenylsulphonyl]-2-imino-3-cyclopentylimidazolidine-dihydrochloride and 13.7 g. of chloroformic acid-isobutylester, 1-[p-(2-(isobutoxycarbonylamino)-ethyl)-phenylsulphonyl]-2-imino-3-cyclopentylimidazolidine, M.P. 144-145°.

What is claimed is:

1. A compound of formula

wherein

R₁ is alkyl of from one to six carbon atoms, cycloalkyl, cycloalkenyl, alkyl substituted cycloalkyl or alkyl substituted cycloalkenyl of from five to eight carbon atoms, or allyl;

R₂ is hydrogen, methyl or ethyl;

R₃ is alkyl of from one to six carbon atoms, cycloalkyl or alkyl substituted cycloalkyl of from five to eight

carbon atoms, allyl, phenyl or phenylalkyl of at most three carbon atoms in the alkyl chain; and m is the integer 2 or 3;

or the pharmaceutically acceptable acid addition salts thereof.

5 2. A compound according to claim 1, which is 1-[p-[2-ethoxycarbonylamino)-ethyl]-phenylsulfonyl] - 2-imino-3-cyclohexyl-imidazolidine.

10 3. A compound according to claim 1, which is 1-[p-[2-(ethoxycarbonylamino)-ethyl]-phenylsulfonyl] - 2-imino-3-cyclopentyl-imidazolidine.
